DESIGN.

J. PIRKL.
WINDOW GUARD.

No. 18,293.

Patented May 1, 1888.

UNITED STATES PATENT OFFICE.

JOHN PIRKL, OF BROOKLYN, NEW YORK.

DESIGN FOR A WINDOW-GUARD.

SPECIFICATION forming part of Design No. 18,293, dated May 1, 1888.

Application filed December 16, 1887. Serial No. 258,139. Term of patent 7 years.

To all whom it may concern:

Be it known that I, JOHN PIRKL, a citizen of the United States, residing at Brooklyn, in the county of Kings and State of New York, have invented and produced a new and original Design for Window-Guards; and I do declare the following to be a full, clear, and exact description of the same, reference being had to the accompanying photograph, forming a part

to thereof.

The present invention has relation to the design for ornamental gates and window-guards; and it consists, substantially, of the ornamental form and configuration illustrated in the accompanying photograph and hereinafter described and claimed.

The photograph forming a part of this specification represents a front elevation of a gate or window-guard in accordance with my design, which will now be described. This gate or window-guard consists, substantially, of an outer frame composed of two parallel bars, A B, extending around the four sides of the inner ornamental portion of the device and inclosing it, as shown. Joining the two bars above referred to are curved bands c, which extend transversely to the length of the bars, which form together an ornamental frame-work of the gate or guard. At or near the central portion of the gate or guard is a row of rosettes,

C, inclosed by circles b, the said circles extending out from the sides thereof tapering loops D, and from the largest or outer ends of these loops the extremities terminate in scrolls e d. The loops D upon the opposite side of the line 35 of rosettes terminate in V-shaped ornaments e. One end of the inclosing-frame has a bar extending transversely with the length thereof and its ends joining the inner bar of the frame, and between the inner frame bar and the bar 40 f are scrolls E F.

Having now fully described my invention, what I claim as new, and desire to secure by Letters Patent, is—

A design for gates or window-guards, consisting of an outer or inclosing frame composed of two parallel bars having transverse bands joining the bars, a row of rosettes, each encircled by a ring, loops upon each side of the line of the circles, and a line of scrolls or ornaments 50 between the ends of the loops and inclosing-frame, substantially as shown and described.

In testimony whereof I affix my signature in presence of witnesses.

JOHN PIRKL.
